BY DIRECT AND MESNE ASSIGNMENTS, TO HOESCHEN MANUFACTURING COMPANY,
OF OMAHA, NEBRASKA, A CORPORATION OF NEBRASKA.

RAILWAY-SIGNAL-ACTUATING MECHANISM.

1,196,236.

Specification of Letters Patent. Patented Aug. 29, 1916.

Application filed August 19, 1913. Serial No. 785,546.

To all whom it may concern:

Be it known that we, HENRY A. HOESCHEN and JOSEPH A. HOESCHEN, citizens of the United States, and residents of Omaha, in the county of Douglas and State of Nebraska, have invented certain new and useful Improvements in Railway-Signal-Actuating Mechanism, of which the following is a specification.

10 Our invention relates to railway signaling mechanism, and it is the object thereof to provide a simple and positive means for actuating or controlling such signaling mechanism, utilizing as a motive force the 15 deflections or undulations caused in railway-track rails by the passage of trains over them.

A further object of our invention is to provide means for rendering the action of 20 the mechanism selective or in accordance with the direction of movement of the train causing the rail deflections or undulations.

Other and more specific objects of our invention will appear hereinafter.

25 In the accompanying drawings Figure 1 is a side view of a rail having applied thereto devices embodying our invention, Fig. 2 is a detail transverse section on the plane of the line 2—2 of Fig. 1, Fig. 3 is a detail section on the plane of the line 3—3 of Fig. 1, Figs. 4, 5 and 6 are diagrammatic views illustrating the movements of the needle-beam caused by deflections of the rail, Fig. 7 is a longitudinal vertical section of the 30 generator-casing on the plane of the line 7—7 of Fig. 8, Fig. 8 is a transverse vertical section on the plane of the line 8—8 of Fig. 9, Fig. 9 is a horizontal section on the plane of the line 9—9 of Fig. 8, and Fig. 40 10 is a detail side view of the shunt-switch.

The steel rails regularly employed in the construction of railway tracks are flexible enough so that pressure thereon of the wheels of cars and engines of normal weight 45 is sufficient to cause measurable deflections of the rails. These deflections appear to be in the form of curved depressions of the rail-body, the radii of curvature, of course, being very great, the center of curvature being coincident with the wheel-axis when the latter is stationary, but probably lagging behind the wheel-axis more or less when the same is in motion. It will be apparent that when a wheel is in motion along a rail the

depression of the rail beneath the wheel will 55 move along the rail and will constitute a longitudinally progressing wave-movement in the rail-body. It will also be obvious that the amount of depression or sag of the rail will bear a proportional relation to the 60 rigidity of the rail itself and of the road-bed on which the track is laid, and to the weight of the train whose wheels rest upon and move along the rail; but it has been found by experiment that in practice there 65 is always a sufficient depression of the rail to effect the operation of mechanism constructed in accordance with our invention.

In carrying out our invention we provide a needle-beam 11 which is disposed alongside a railway-track rail 12, one end of the needle-beam being rigidly secured to the rail and all the remainder of the beam being in proximity to but not secured to the rail. A simple and convenient means for securing 75 the beam to the rail is furnished by the clamps shown clearly in Fig. 2. Each of said clamps comprises a member 13 fitting around one side of the base-flange of the rail and having an upwardly extending lug 80 14 thereon, a similar member 15 fitting around the other side of the rail base-flange, and a bolt 16 passing through the lower parts of the members 13 and 15, the bolt having a nut which is screwed up so as to 85 force the members toward each other and retain them securely upon the rail. Two of the clamps are preferably secured upon the rail adjacent to each other, as shown in Fig. 1, and the needle-beam secured to the 90 lugs 14 by rivets 17. The needle-beam may be of rectangular section, disposed with the longer sides of the section parallel with the rail-web, and is preferably tapered toward the free or unsecured end thereof, as shown 95 in Fig. 1.

Referring now to Figs. 4, 5 and 6, the movements of the needle-beam caused by the rolling of a wheel along the rail will be apparent. In said figures the rail and beam 100 are represented by single lines which may be considered as the longitudinal axes of the members. When there is a deflection of the rail causing a curvature of the rail-axis at the point of connection between the rail and 105 needle-beam, the axis of the latter will, obviously, extend tangentially to the curve of the rail-axis. It is assumed that normally

the rail and beam-axes are parallel, and in the depression of the rail beneath the wheel W the amount of deflection is shown by comparison with the dotted line which indicates 5 the normal position of the rail-axis. If the wheel W is considered as moving from left to right, then Figs. 4, 5 and 6 represent the successive relations of the rail and beam during the movement of the wheel toward, over 10 and beyond the point at which the needle-beam is secured to the rail. From the respective figures it will be seen that as the wheel, moving to the right, approaches the point of connection between the rail and beam the free end of the beam will be first moved upwardly, then downwardly to a position parallel with the rail as the wheel is directly above the point of connection, and will have a further downward movement as 15 the wheel passes on to the right of the point of connection. If the wheel be considered as moving to the left, the successive directions of movement of the free end of the beam will be reversed, said end of the beam moving first downwardly from the normal 20 position and then upwardly. The extent of the movement of the free end of the beam will be greater or less according to the length of the beam from said free end to the point of connection with the rail, but whenever the beam is of any considerable length the movement of the free end will be greater in extent than the undulations in the rail-body. The said movements of the needle-beam may be utilized for any desired purpose, but are peculiarly adaptable to actuate or to control signal mechanism, and such signal mechanism may serve either to simply indicate the passage of trains over the 25 track at the point where the needle-beam is located, or to indicate the movement of trains past said point in a particular direction.

In the structure shown in the drawings the 30 movements of the needle-beam are employed to actuate a magneto-electrical generator, which may be connected in an electrical circuit extending to mechanism located at a distance therefrom, so that the electrical impulses produced by the generator may actuate or control said distant mechanism.

The generator comprises U-shaped permanent magnets 18 which are provided with pole-pieces 19, coils 20 disposed around the 35 pole-pieces, and a pivoted armature 21 which is normally in contact with the ends of the pole-pieces. The generator is inclosed in a suitable casing 22 of non-magnetic metal, the magnets 18 being disposed 40 in a horizontal position, the pole-pieces and coils depending from the ends of the magnets, and the armature engaging the lower ends of the pole-pieces. The armature is inclosed by a removable plate 23 secured on 45 the lower side of the casing, a small coil

spring being disposed between the said plate and the armature to press the latter yieldingly upward. The upper side of the casing 22 also has a removable cover-plate 24. The casing is fixedly secured to the rail 12 beneath the free end of the needle-beam, there being on the cover-plate 24 a hook-shaped lug 25 fitting around one side of the rail base-flange, a clamp-member 26 fitting around the opposite side of the base-flange, 75 and a bolt 27 passing through the lug and the member 26 to hold them securely upon the rail.

To the end of the needle-beam is pivotally connected a rod 28 which extends downwardly into the generator-casing through a packing-gland 29 in the cover-plate 24, the rod terminating just above the free end of the armature 21, after passing through a guide 30. Secured upon the rod 28 midway 80 between the guide 30 and cover-plate 24 is a collar 31. As a means of deadening and quickly suppressing mere vibratory movements of the needle-beam, the springs 32 and 33 are placed around the rod 28 above 85 and below the collar 31. The springs are inclosed and held under a certain normal compression by means of cylindrical casings disposed around them, as shown. Said casings comprise tubular parts 34 secured respectively to the cover-plate and to the casing adjoining the guide 30, and cup-shaped parts 35 slidable within the tubular parts, the adjoining ends of the casing-parts having shoulders which are normally held in engagement with each other by the pressure of the springs on the parts 35. The closed ends of the parts 35 engage the upper and lower sides of the collar 31 so that upward movement of the rod 28 will increase the compression of the spring 32, while downward movement of the rod will increase the compression of the spring 33. The springs 32 and 33 are so proportioned and the initial or normal compression thereof is such that while they will prevent or quickly suppress any mere vibratory movements of the needle-beam, they will not prevent the forcible movements thereof occasioned by deflections 90 of or undulatory movements in the rail-body.

Adjacent to the rod 28 a cylinder 36 is formed in the casing 22, and within the cylinder is disposed a loosely-fitting tubular piston 37 from which a piston-rod 38 extends slidably through a plug 39 screwed into the upper end of the cylinder. At the upper end of the piston-rod is a head 40. A finger 41 is secured to the side of the collar 31 and extends upwardly and laterally therefrom, terminating beneath the head 40, so that when the needle-beam and rod 28 move upwardly from the normal position thereof said finger will engage the head 40 and move the piston-rod and piston upwardly. 130

A spring 42, disposed around the piston-rod within the cylinder, is compressed during the upward movement of the piston and tends to return the piston to the normal position thereof at the bottom of the cylinder. In the lower central part of the piston is a transverse web 43 to which the lower end of the piston-rod is attached, and on the lower side of said web is a valve-plate 44 which is 5 slideable vertically on a stud 45 that extends down from the web. A spring 46 disposed around the stud normally holds the valve-plate against the web so that the openings through the web are closed by the plate. 10 The cylinder is filled with a suitable fluid, preferably an oil of such quality as to remain liquid at low temperatures. When the piston is raised in the cylinder the fluid passes down through the valve, which closes 15 20 as the upward movement ceases, and thus prevents the return of the liquid through the web to the upper part of the cylinder. The downward pressure exerted by the spring 42 will, however, force the piston slowly downward, the liquid returning from the lower to the upper part of the cylinder by leakage around the piston which, as before noted, fits loosely in the cylinder. Thus when the piston is raised it will remain for a certain 25 30 time in a more or less elevated position, but within a determinable time will return to the normal lower position.

In a lateral extension of the casing 22 adjacent to the head 40 is arranged a shunt-switch comprising a contact-plate 47 and a contact-spring 48 which are suitably insulated from each other and from the casing, and which extend out into proximity to the head 40 as shown in Fig. 8. Above the contact-spring 48 and insulated therefrom is a spring-plate 49 of which the free end extends beneath the head 40. When the piston-rod is in the normal lower position thereof the parts 48 and 49 are pressed down 35 40 45 by the head 40 so that the contact-spring 48 is in engagement with the upturned end of the contact-plate 47. The parts 48 and 49 are formed so that they tend to curve upwardly to a position such as shown in Fig. 50 55 10, at which the spring 48 is disengaged from the plate 47. Thus when the piston-rod is raised the contact between the switch-parts is broken and the switch remains open until the piston resumes its normal lower position.

In Fig. 9 the generator-coils 20 are shown as connected with wires 50 which pass out of the casing 22 through a pipe 51 and which may extend to any suitable electrical signal 60 or other appliance that it may be desired to actuate or to control by means of the current produced by the generator. In said Fig. 9 the coils 20 are also shown as connected by wires 52 in parallel with the shunt-switch contact-pieces 47 and 48,

The operation of the entire mechanism shown and described will now be apparent, and may be briefly summarized as follows: A wheel W moving along the rail in one direction will cause first an upward movement 70 and then a downward movement of the free end of the needle-beam relatively to the rail. A wheel moving in the other direction along the rail will cause first a downward movement and then an upward movement of the 75 free end of the needle-beam relatively to the rail. These movements of the needle-beam relatively to the rail cause like movements of the rod 28 relatively to the casing 22 and the mechanism carried thereby. Movement 80 of the needle-beam upwardly from the normal position thereof causes an elevation of the piston-rod and a consequent opening of the shunt-circuit made through the switch-parts 47 and 48, and the retardation of the 85 downward movement of the piston causes the shunt-circuit to be held open for a determinable time. Movement of the needle-beam downwardly from the normal position causes the rod 28 to displace the armature 21 90 from the pole-pieces 19 and generates an electrical impulse in the coils 20. If the shunt-circuit be closed when the impulse is generated in the coils it is obvious that practically the entire current produced will 95 pass through the shunt-circuit, since the resistance thereof would be negligible as compared with that of the line-circuit made through the wires 50. Should the shunt-circuit be open when the impulse is generated in the coils, the entire current must 100 pass through the line-circuit. Thus the causation of an effective current in the line-circuit may be made dependent on the direction of movement of the wheel W along 105 the rail; the current passing to the line-circuit when (the first movement of the needle-beam being upward) the shunt-circuit is opened prior to the generation of the electrical impulse; and no effective current 110 passing to the line-circuit when (the first movement of the needle-beam being downward) the impulse is generated prior to the opening of the shunt-circuit.

It will be clearly seen by those skilled in 115 the art that our invention has a wide range of utility and applicability, and that the scope of the invention is not limited to the specific structures herein shown and described, such structures being merely illustrative species comprised within the generic idea of means constituting the primary invention.

Now, having described our invention, what we claim and desire to secure by Letters Patent is:

1. The combination with a railway-track rail, of a beam disposed adjacent to the rail, and substantially parallel therewith, and means for securing one end of said beam to 130

the rail, so that deflections of the rail at the point of connection of the beam therewith will cause movements of the free end of the beam relatively to that portion of the rail adjoining the same.

5 2. The combination with a rail forming part of a railway track, of a needle-beam disposed adjacent to the rail and extending longitudinally thereof and having one of its 10 ends rigidly secured to the rail, whereby undulatory movements of the rail at the secured end of the needle-beam will cause oscillatory movements of the free end of the needle-beam.

15 3. The combination with a railway-track rail, of a beam having a part thereof attached to the rail and a portion extending free and substantially parallel with the rail to a considerable distance from the rail- 20 attached part, whereby slight undulations in the rail-body will cause movements of the free portion of the beam greater in extent than the undulations.

25 4. The combination with a railway-track rail, of a rectilinear beam having a portion rigidly secured to a part of the rail and extending longitudinally thereof, so that during longitudinal bending of the rail-body into a curve including said part the beam 30 will extend tangentially to the curve.

35 5. In a railway signaling mechanism, a track-rail, and a member having a part fixedly secured to a portion of the rail and another part extending adjacent to a portion 40 of the rail remote from the first, whereby the relations of the latter parts of the member and the rail are variable by longitudinally progressing wave-motions in the rail-body, and the initial directions of said variations are in accordance with the directions of progression of the wave-motions.

45 6. In a railway signaling mechanism, a track-rail, a beam having one end rigidly secured to the rail, the other end of the beam being free and extending adjacent to the rail at a point distant from the point of connection of the rail and beam, an electrical circuit, a switch controlling said circuit, means mechanically connecting the switch with the 50 rail adjacent to the free end of the beam, and means connected with said end of the beam for controlling the switch by movements of said end of the beam relatively to the adjacent portion of the rail.

55 7. In a railway signaling mechanism, a track-rail, a needle-beam having one end fixedly secured to the rail and a free portion extending adjacent to the rail remote from the secured end, resilient means connected 60 with the rail adjacent to the free portion of the beam, and means connected with said portion of the beam and engageable with said resilient means.

65 8. In a railway signaling mechanism, a track-rail, a needle-beam having a portion

fixedly attached to the rail and a free portion extending adjacent to the rail at a point remote from the attached portion, a pair of compressible parts connected with the rail adjacent to the free portion of the beam, 70 means for normally retaining said parts under a certain stress, and means connected with the free portion of the needle-beam and co-operating with the compressible parts to restrain vibratory movements of said portion of the beam relatively to the adjacent portion of the rail.

9. In a railway signaling mechanism, a track-rail, a magneto-electrical generator disposed adjacent to a portion of the rail 80 and having a movable armature, a member having a normal position adjacent to said armature so that movement thereof may actuate said armature, and a needle-beam having one end connected with said member 85 and the other end rigidly connected to a part of the rail remote from the generator.

10. In a railway signaling mechanism, a track-rail, an electrical circuit, means for controlling said circuit, a movable member 90 for actuating said controlling means, and a needle-beam connected with said member, the needle-beam extending to a part of the rail remote from the movable member and being rigidly secured to said rail-part. 95

11. In a railway signaling mechanism, a track-rail, a casing secured to the rail, a magneto-electrical generator disposed in said casing, an electrical circuit connected with said generator, a switch disposed in 100 the casing and controlling said circuit, a movable member extending into the casing for actuating the generator and the switch, and a needle-beam connected with said member, the needle-beam extending to and being 105 rigidly secured to a part of the rail remote from the casing.

12. In a railway signaling mechanism, a track-rail, a casing secured to said rail, a magneto-electrical generator disposed in 110 said casing, an electrical circuit connected with said generator, a switch disposed in the casing and controlling said circuit, a reciprocatory member extending into the casing and adapted to actuate the generator by movement in one direction from a normal position and to control the switch by movement in the other direction from said normal position, and means for actuating said member from normal position initially in accordance with the direction of longitudinally progressing wave-motions in the rail. 115

13. In a railway signaling mechanism, a track-rail, an electrical circuit, a switch controlling the electrical circuit, a movable member for actuating the switch, means tending to move said member in one direction, means for retarding movement of the member in said direction, an actuating part 125 for moving the member in the other direction. 120

tion, and means connecting said part and the rail so that the initial movement thereof from normal position is in accordance with the direction of longitudinally progressing wave-motions in the rail-body.

14. In a railway signaling mechanism, a track-rail, a rigid member having a part secured to the rail and a free part extending to a point remote from the secured part, the said free part being movable initially from normal position in accordance with the direction of longitudinally progressing wave-motion in the rail, an electrical circuit, means controlling said circuit, and means connected with the free part of said rigid member for actuating said controlling means.
15. In a railway signaling mechanism, a track-rail, a rigid member secured to the rail and having a free part movable initially from a normal position in accordance with the direction of longitudinally progressing wave-motions in the rail, an electrical circuit, a generator connected in said circuit, a switch controlling said circuit, a reciprocating part for actuating the switch, means for retarding movement of said part in one

direction, and means connected with the free part of the rigid member and movable thereby to actuate the generator and the reciprocating part alternately.

16. In a railway signaling mechanism, a track-rail subject to longitudinally progressing undulations in the body thereof, a member fixedly secured to the rail so as to be moved in alternating directions by the undulations of the rail-body, the initial movements of said member from normal position being in accordance with the direction of progression of the undulations along the rail, means actuated by movement of the member in one direction from its normal position, and other means actuated by movement of the member in the other direction from its normal position.

In testimony whereof we have hereunto subscribed our names in the presence of two witnesses.
